UNITED STATES PATENT OFFICE.

HAROLD W. A. DIXON, OF HOLLIS, NEW YORK, ASSIGNOR TO COLUMBIA RIBBON & CARBON MANUFACTURING COMPANY, INC., OF NEW YORK, N. Y., A CORPORATION OF NEW YORK.

WIDE FABRIC PREPARED TO BE SLIT AND METHOD OF PREPARING THE SAME.

Application filed January 18, 1928. Serial No. 247,473.

The present invention is related to the art of slitting wide fabrics into narrow strips and is particularly useful in making typewriter ribbons and the like, my improved method 5 and apparatus effecting a considerable saving in the fabric in slitting the same, and more efficient results being obtained.

In the manufacture of typewriter ribbons, for example, under present methods, a roll of 10 cloth is clamped upon an arbor, the arbor and cloth roll then being rotated as a rotatable cutter is brought into contact with the cloth, thereby slitting the cloth to the desired width. This method, however, is unsatisfactory com- 15 mercially owing to the difficulty experienced in properly holding the roll so that the same can be slit satisfactorily adjacent the clamped end, resulting in waste of material, uneven cutting and generally unsatisfactory results.

20 The present method and apparatus provide for retaining the roll of cloth in place with sufficient stability and rigidity to permit of the cloth to be slit or cut evenly and practically the entire roll to be utilized.

25 In the accompanying drawings,

Fig. 1 is a view in sectional elevation of an apparatus by which my invention may be practiced; and

30 Fig. 2 is a view on the line 2—2 of Fig. 1 looking in the direction of the arrows.

In the practice of my invention a strip of adhesive paper, tape or other suitable some- 35 what stiff material 2 is wrapped about the drive end of a roll of fabric 3 to be slit, as illustrated in Fig. 1, this paper 2 being applied so that a portion thereof will project beyond the drive end of the roll to provide a cup-shaped depression 4.

40 A spider 7 is then placed in the depression thus formed, this spider being provided with a hub 8 which is slipped over the cardboard tubing 9 on which the fabric is rolled. With the roll standing on end and the spider 8 in place wax is poured into the depression 4, this wax or other suitable material which is designated 5, flowing between the turns or wraps of the roll to unite the spider and roll into a solid unitary structure. The roll 3 and spider 7, are then slipped over the arbor 10, 45 and the hub 8 of the spider attached to the drive for the arbor 10 by a set screw 11. The roll 3 may then be rotated and a rotatable cutter 12 brought into operative relation

thereto to slit the cloth as I have indicated at 13.

55 As will be understood, the cutter is ad- vanced longitudinally of the roll 3 after each slitting operation of the cutter 12 and by rea- son of the manner in which the inner end of the roll has been treated it will be obvious 60 that the roll will be sustained sufficiently rigid to enable the cutter to slit the cloth up to the point where the strip 2 overlaps which is prac- tically to the extreme end of the roll eliminat- 65 ing practically all waste of material.

70 The foregoing method, therefore, provides a method and apparatus which greatly facil- itates the slitting of wide fabrics into narrow- 75 er widths, providing a method and apparatus whereby not only may the entire roll, practi- cally, be utilized, but the roll will be sustained with sufficient rigidity and stability to enable the desired even slitting to be produced, there- 80 by eliminating the difficulties experienced heretofore in this art.

75 What I claim is:—

1. In the slitting of wide fabrics into nar- 85 row widths, the method of preparing the fab- ric for slitting which consists in applying an annular extension to a roll of the fabric and filling the depression thus formed with a self-hardening material thereby to unite the extension, roll and the ends of the wraps of the material constituting the roll into a solid 90 rigid structure.

2. In the slitting of wide fabrics into nar- 95 row widths, the method of preparing the fab- ric for slitting which consists in applying an annular extension to a roll of the fabric, at- taching a coupling member to the end of the roll within the depression thus formed by placing the coupling member within the de- 100 pression and filling around the same with a self-hardening material while allowing this material to flow between the wraps constitut- 105 ing the roll.

3. In combination a roll of material to be slit into narrow widths, an extension at one end of the roll, providing with the roll a cup- 110 like depression, a self-hardening material in said depression, and a coupling member at- tached to said self-hardening material.

4. In combination a roll of material to be slit into narrow widths, a relatively stiff material wrapped about one end of said roll 115 and projecting beyond the same to provide a

depression at the roll end, a self-hardening material in said depression, and a coupling member attached to the roll by said self-hardening material.

5. In combination a roll of material to be slit into narrower widths, an extension on said roll providing a depression at the end of the roll, a self-hardening material in said depression and contacting with the material of

the roll and lying between the ends of the 10 wrap composing the roll, and a coupling member embedded in said self-hardening material, whereby the coupling member is attached to the roll and the end of the roll converted into a rigid structure. 15

This specification signed this 16 day of January, 1928.

HAROLD W. A. DIXON.
